UNITED STATES PATENT OFFICE

GEORGE W. BORTON, OF NEW LISBON, NEW JERSEY, ASSIGNOR TO PENNSYLVANIA CRUSHER COMPANY, OF NEW YORK, N. Y., A CORPORATION OF NEW YORK

CRUSHING MACHINERY

Application filed December 12, 1929. Serial No. 413,474.

My invention relates to crushing machinery of the type employing rotor structures carrying hammers which engage material delivered into their path and effect breakage or rupture thereof by beating the same against a breaker plate or plates forming one wall or part of one wall of the crushing chamber.

Certain materials which may originally contain a high moisture content or which may be subject to wet conditions during transit between the point of excavation and the point of crushing become so sticky that, in the operation of reducing the same, a mass of highly viscous mud builds up on the breaker plate and seriously affects the capacity of breaking machinery of this type.

The main object of my invention, therefore, is to provide means that will prevent this building up of a body of mud upon the breaker plate.

A further object of my invention is to provide scraping means for the breaker plate which will serve to keep the same clean or substantially so during the crushing operation.

And a still further object of my invention is to provide a swinging scraping blade or arm and means for operating the same.

These and other features of my invention are more fully described hereinafter; reference being had to the accompanying drawings, in which:

Figure 1 is a cross sectional view of one form of crushing structure within the scope of my invention, showing scraping means associated with the breaker plate thereof.

Fig. 2 is a view in elevation of the breaker plate and scraping blades associated therewith looking in the direction of the arrow x , Fig. 1.

Figs. 3 and 4 are views similar to Fig. 2 illustrating modified arrangements of scraping blades within the scope of my invention.

Figs. 5, 6, 7 and 8 illustrate, more or less diagrammatically, other scraping blade arrangements within the scope of my invention, and

Fig. 9 is a sectional view on the line IX—
IX, Fig. 2.

While applicable to many forms of crushing machinery, in the present instance I have shown my improved breaker plate and scraper construction as applied to crushing machinery of the type illustrated in my pending application, filed August 25, 1928, Serial No. 302,080, in which the crushing chamber is provided with a series of grid bars. These grid bars when employed may be carried by or associated with one wall of the crushing chamber so as to temporarily retard large masses of material to be crushed which are acted upon by the uprunning hammers as they pass between the grid bars.

In carrying out my present invention, I may associate with that part of the frame of the machine which may be termed the wall of the crushing chamber and indicated generally at 1, an auxiliary support or frame 2, which may be secured thereto in any appropriate manner, as by the bolts 3, and to this support a breaker plate 4 having a substantially flat surface is secured. In the present instance, this breaker plate is indicated as inclined slightly with respect to the perpendicular and extends the full width of the crushing chamber, as clearly indicated in Fig. 2. If desired, the wall 1 may be constructed with a flat face to take the place of the supplemental members 2 and 4, or the member 4 may be secured to such flat face, and in any of these arrangements the active breaking surface of the plate or wall may be vertically disposed instead of being inclined as indicated in Fig. 1.

Crushing machinery of this type is provided with a hammer-carrying rotor structure of the character illustrated in my application before referred to, and such rotor structure may include a shaft 5, suitably journaled, carrying disks 6, supporting rods 7, upon which hammers 8 are mounted. The wall 1 of the crushing chamber may support a series of grid bars 9 between which the hammers pass, although it will be understood that such grid bars may be omitted in the use of the construction forming the subject of my present invention.

For the purpose of preventing any building up upon the breaker plate or the breaking

surface with which the hammers cooperate, of the material being crushed or reduced, I provide removing means in the form of scraping blades 10, arranged to pass over the breaking 5 plate or the breaking surface. In the form illustrated in Figs. 1 and 2, the scraping blades are carried by rock shafts 11, which may be suitably mounted or journaled in the support 2 for the flat breaker plate or the wall, and 10 these rock shafts may be driven in any suitable manner; separately driven if desired, or driven in unison as the case may be. For this purpose these shafts may be provided with pinions 12, which may be engaged by rack 15 rods, or such shafts may be driven by any means that will insure the desired rocking or swinging movement and total movement of the respective blades to an extent of 180°, in the form illustrated in Fig. 2.

20 As illustrated in Fig. 2, the blades may be set in opposite positions with respect to each other so that when they are rocked one blade will describe an arc of 180° in one direction and the other blade will describe a similar arc 25 in the opposite direction. This scraping action will serve to keep the breaker plate clean throughout the major portion of the same, while it is possible that masses of the material may build up in the substantially V-shaped 30 spaces between the paths of the scraping blades, it is believed that such masses will be broken down by the oncoming material during operation of the machine.

Other arrangements of the scraping blades 35 may be employed, and in Figs. 3 and 4, I have shown forms of depending blades which are mounted near the top of the substantially flat breaker plate or breaking surface, indicated at 4^a and 4^b respectively. In the arrangement 40 illustrated in Fig. 3, two blades 10^a may be mounted upon shafts 11^a which may be journaled in the upper part of the breaker plate or breaking surface 4^a, and these blades are arranged to sweep across the breaker 45 plate; covering in their action the major portion of the same. These blades are preferably set with relation to each other in the position indicated in Fig. 3, so that in their scraping movements they follow each other just out of 50 contact. While their scraping action will leave a small portion of the breaker plate near the lower portion of the same untouched, this portion is directly in the path of the oncoming material, and there will be little tendency 55 of the sticky portion thereof to build up unduly.

In the arrangement illustrated in Fig. 4, a single blade 10^b may be set centrally with respect to the upper portion of the breaker plate 60 or breaking surface 4^b, and may be carried by a shaft 11^b. The shaft may be rocked so as to move this blade back and forth over the lower portion of the breaker plate or breaking surface by means similar to those employed in 65

connection with the rock shafts of the other structures.

Other arrangements of the scraping blades are illustrated more or less diagrammatically in Figs. 5, 6, 7 and 8. In Fig. 5, I have shown a pair of blades 10^c carried by rock shafts 11^c, in substantially the same manner as those illustrated in Fig. 3, excepting that the supporting rock shafts by which motion is imparted to said blades are mounted above the 75 breaking surface, indicated at 4^c. In Fig. 6, I have shown a single blade 10^d, centrally disposed midway the length of the breaking surface 4^d, and carried by a rock shaft 11^d, mounted above such breaking surface. 80

In Fig. 7, I have shown a single scraping blade 10^e mounted on a rock shaft 11^e disposed substantially centrally with respect to the breaking surface 4^e. This single blade may be continuously rotated, in either direction, for the purpose of keeping such breaking surface relatively free from the mud or slimy portions of the material undergoing crushing and tending to build up on said breaking surface. In Fig. 8, I have also shown a single 90 scraping blade 10^f which may be mounted on a rock shaft 11^f disposed at one corner of the breaking surface 4^f; preferably a lower corner, and in the present instance such blade is shown as pivotally mounted at the lower right hand corner. The broken lines indicate the 95 range of movement of the several scraping blades illustrated in Figs. 5, 6, 7 and 8.

By preference, the blades have a cross section substantially like that illustrated in Fig. 9, being rounded on top as indicated at *a* and having side cutting edges *a'*; the under surface being inclined away from said cutting edges and merging with the concave under side of the blade. It will be understood, however, that I do not wish to be limited to this particular form of blade, since other forms may be employed without departing from my invention; the important point being to provide suitable forms of scraping blades which 105 may be moved across the breaker plate and prevent objectionable accumulation of the sticky or slimy portion (or portions) of the material operated upon. 110

I claim:

1. The combination, in crushing machinery, 115 of a rotor structure having hammers, a breaking surface against which material undergoing crushing may be thrown by the action of said hammers, and a scraper blade movable across the face of said breaking surface.

2. The combination, in crushing machinery of the rotary beater type, of a rotor structure 125 having hammers, a breaking surface against which material undergoing crushing may be thrown by the action of the hammers, and a pivotally mounted scraper blade movable across the face of said breaking surface.

3. The combination, in crushing machin- 130

ery, of a rotor structure having hammers, a breaking surface against which material undergoing crushing may be thrown by the action of said hammers, and a plurality of 5 scraper blades movable across the face of said breaking surface out of contact with each other.

4. The combination, in crushing machinery of the rotary beater type, of a rotor structure 10 having hammers, a breaking surface against which material undergoing crushing may be thrown by the action of said hammers, and a plurality of pivotally mounted scraper blades 15 movable across the face of said breaking surface out of contact with each other.

5. The combination, in crushing machinery of the rotary beater type, of a rotor structure having hammers, a flat breaker plate against which material undergoing crushing may be 20 thrown by the action of said hammers, a pivotally mounted scraper blade movable across the face of said breaker plate, and a rock shaft supporting said blade.

6. The combination, in crushing machinery 25 of the rotary beater type, of a rotor structure having hammers, a flat inclined breaker plate against which material undergoing crushing may be thrown by the action of said hammers, a pivotally mounted scraper blade movable 30 across the face of said inclined breaker plate, and a rock shaft supporting said blade.

7. The combination, in crushing machinery of the rotary beater type, of a rotor structure having hammers, a flat inclined breaker plate 35 against which material undergoing crushing may be thrown by the action of said hammers, a plurality of pivotally mounted scraper blades movable across the face of said inclined breaker plate, and independent rock shafts 40 supporting said blades.

8. The combination, in crushing machinery, of a rotor structure having hammers, a breaker plate against which material undergoing crushing may be thrown by the action 45 of said hammers, a pivotally mounted scraper blade movable across the face of said breaker plate, a rock shaft supporting said blade, and means for imparting movement to said rock shaft.

50 9. The combination, in crushing machinery of the rotary beater type, of a rotor structure having hammers, a breaker plate against which material undergoing crushing may be thrown by the action of said hammers, a pivotally mounted scraping blade movable across 55 the face of said breaker plate, a rock shaft supporting said blade, and means for imparting movement to said rock shaft.

10. The combination, in crushing machinery 60 of the rotary beater type, of a rotor structure having hammers, a breaker plate against which material undergoing crushing may be thrown by the action of the hammers, a plurality of pivotally mounted scraping blades 65 movable across the face of said breaker plate,

independent rock shafts supporting said blades, and means for imparting movement to said rock shafts.

11. The combination, in crushing machinery of the rotary beater type, of a rotor structure having hammers, a breaker plate against which material undergoing crushing may be thrown by the action of said hammers, a plurality of pivotally mounted scraping blades 70 movable across the face of said breaker plate, independent rock shafts supporting said blades, pinions carried by said rock shafts, and a reciprocating rack bar in engagement with said pinions for rocking said shafts.

In witness whereof I have signed this specification.

GEORGE W. BORTON.
